UNITED STATES PATENT OFFICE.

JOHN MURTON BROWN, OF IRVINGTON, NEW JERSEY, ASSIGNOR TO CRYSTAL OIL BURNER CORP., OF IRVINGTON, NEW JERSEY, A CORPORATION OF NEW JERSEY.

FUEL PROPELLING AND MIXING DEVICE.

Application filed April 6, 1927. Serial No. 181,309.

This invention relates to blowers and more particularly to blowers of the type especially adapted for delivering atomized oil to a source of consumption, such as an oil burner.

5 It is an object of my invention to provide a blower which is adapted to receive a mixture of oil and air and deliver the same at a uniform pressure and in a continuous manner while maintaining the uniformity of 10 said mixture.

Another object of the invention is to provide a blower which is adapted to deliver a mixture of oil and air and which at the same time operates upon the oil and air to form 15 a more intimate mixture thereof and to more finely divide the oil particles.

Another object of the invention is to provide a vacuum-centrifugal blower.

Another object of the invention is to provide 20 an atomized oil blower which is so constructed that "puddling" of the oil does not take place therein.

A still further object of the invention is to provide mechanism which is adapted to 25 atomize oil and to deliver said atomized oil in a continuous manner and at a uniform pressure.

A still further object of the invention is to provide a system for delivering crude oil 30 to an oil burner in such condition that it may be "cracked" to form a combustible fuel.

Other objects of the invention will become apparent as the following detailed description is read.

35 Various devices have been made for conveying liquids and gases from one position to another, but so far as I am aware no such devices are adapted for conveying a mixture of oil and air, that is atomized oil, in a 40 continuous manner and without disturbing the relative proportions of oil and air. The reason why such devices are unsatisfactory for the purpose indicated is because the oil owing to its greater specific gravity than 45 the air collects into pools or puddles within the blower or other device employed for translating the same.

50 My invention is especially adapted for oil burners although other uses therefor may suggest themselves to those skilled in the art. Oil burners of the type for which the invention is particularly adapted are described and claimed in my copending applications, Serial Number 696,187, filed March 55 1, 1924, Serial Number 728,537, filed July 28,

1924, and Serial Number 45,459, filed July 23, 1925. Such oil burners require the delivery thereto of a mixture of crude oil and air in proper proportions and at a uniform speed and pressure inasmuch as the "cracking" of the oil by the burner is partially dependent upon these factors. It is also desirable that the oil and air be intimately mixed and that the oil is in as fine a state of subdivision as is capable of being attained. 60 65

The present invention has been devised especially to fulfil the above-mentioned needs inasmuch as blowers of the type at present found on the market are unsatisfactory for this purpose although such 70 blowers may be entirely suitable for either conveying a liquid or a gas alone, but not for conveying a mixture thereof and maintaining its uniformity.

An embodiment of my invention may 75 comprise a casing in which is mounted for rotation a rotor consisting of a skeleton frame supporting a plurality of blades of various sizes. These blades are so arranged with respect to each other and with respect 80 to the center of the rotor member as to draw a mixture of oil and air in the direction of the axis of the rotor through a centrally disposed opening in one side of the casing. The mixture of oil and air thus drawn with- 85 in the casing is lifted by the rapidly rotating blades due to the shape of the latter toward the periphery of the rotor where through centrifugal action it is driven or thrown to the outer side of the rotor and 90 into the space between the rotor and the casing. The mixture of oil and air thus delivered into the casing is carried around the casing in the direction of rotation of the rotor by the action of the blades until an 95 opening in the casing is reached through which said mixture is forced under considerable pressure. The blades in addition to performing the various functions just described also break up the oil particles into 100 still smaller particles and also cause the air and oil to become more intimately mixed.

Provision is also made in the form of a plurality of auxiliary elongated orifices within the blower adjacent the outlet opening to 105 prevent the oil from "puddling" or collecting into pools. The movement of the mixture of oil and air out of the casing is facilitated by mounting the rotor slightly off center with respect to the axis of the casing, 110

thus providing a chamber in the casing between the rotor and the casing which gradually increases in size toward the outlet therein.

5 A more complete understanding of the invention may be had by reading the following detailed description in connection with the accompanying drawings, in which

10 Fig. 1 is an elevational view of the blower, portions of the casing being broken away to illustrate portions of the interior structure of the blower.

Fig. 2 is a transverse section of the blower taken on line II—II of Fig. 1.

15 Fig. 3 is an elevational view of the face plate of the blower.

Fig. 4 is a sectional view of the cover plate taken on line V—V, in Fig. 3.

20 Fig. 5 is an elevational view of the casing or stator member of the blower.

Fig. 6 is an end view of the casing looking in the direction of the arrows in Fig. 5.

Fig. 7 is an elevational view of the impeller or rotor member of the blower.

25 Fig. 8 is an end view of the impeller or rotor member.

Fig. 9 is an elevational view of the inner end of a primary blade of the impeller or rotor member, and

30 Fig. 10 is a sectional view of the primary blade taken on line XI—XI, in Fig. 9.

An embodiment of my invention may comprise a generally circular casing 12 consisting of a box-like member 13 having a flat 35 wall 14 and a peripheral wall or flange 15 integral therewith. The peripheral wall 15 has a flange 16 projecting outwardly therefrom along its edge and to this flange is bolted a cover plate 17, the fit therebetween 40 being such that no air can enter the casing from the outside thereof. The walls of the casing along their lower edges are shaped so as to form a rectangular passageway 18 which forms the outlet of the casing. The 45 cover plate 17 of the casing is provided near the central portion thereof with an inlet opening 19 through which a mixture of oil and air may be drawn into the casing.

Movement of the mixture of oil and air 50 into the casing is produced by an impeller or rotor 21 which is rotated at a high speed by any suitable source of energy as by a motor 20. The rotor member may comprise a circular disk 22 secured in any desirable 55 manner to a shaft 23 supported in bearings 24 and 25 in an oil or bearing box 26 secured to the wall 14 of the casing. The disk 22 has secured thereto at right angles to its surface and preferably integrally therewith a series of radially disposed plates 60 or vanes consisting of four primary vanes or blades 27, four secondary blades or vanes 28 and thirty-two tertiary blades or vanes 29. The rigidity of the blades is increased 65 by an annular flange 31 which connects

their edges at points located remote from the face of the disk, this flange being preferably integral with the blades. The disk, the blades and the flange are preferably formed as one integral casting although it is obvious that they may be separate elements secured together in any desired manner.

70 The four primary blades are disposed at right angles with respect to the plane of a face of the disk 22 and divide said face into 75 equally sized quadrants 32, 33, 34 and 35. Each of the vanes 27 is bent into the form of a reverse curve, the curved portion 36 being of shorter radius than the curved portion 37, for a purpose which will be more 80 fully described hereinafter. The secondary blades 28 are curved or bent at 38 and are considerably shorter than the primary blades 27. One of the secondary blades 28 is located midway between a pair of primary blades adjacent the outer ends of the latter, thus forming a series of secondary 85 pockets 38'. The tertiary blades 29 are curved or bent at 39 and are about half the length of the secondary blades or vanes 28. 90 There are four tertiary blades disposed in the space between each primary blade and secondary blade so as to divide such space into equally proportioned but lesser capacity 95 pockets 39'.

The curvature of the outer ends of the primary, secondary and tertiary blades is such with respect to the direction of rotation of the rotor as to permit the free passage of the mixture of oil and air therethrough under the centrifugal action of the impeller or rotor, and at the same time such portions of the blades serve to strike the mixture of oil and air in the casing outside of the rotor and propel the same toward and 100 through the passageway or outlet 18. Preferably the curvature should be such that the angle any blade makes with a tangent to the radius of the impeller is less than a right angle, the inner edge of any blade, 105 excepting the primary blades, being at right angles with respect to the tangent of a circle touching the inner edge of the secondary blades.

The inner edges 41 or the edges of the 115 primary blades adjacent the center of the disk 22 is beveled (see Figs. 9 and 10) so that said edges make an angle of about 60 degrees with the face of the disk. This edge of the primary blade is rounded as at 42 (see Fig. 10) and where said edge connects with the upper edge 43 of the primary blades, the surface is rounded, rather sharply, as at 44. The inner edge 45 of the primary blades does not extend to the axial 120 line passing through the center of the inlet opening 19 and disk 17, but is spaced a short distance therefrom. By reason of this construction of the edges 41 of the primary blades, said blades when rapidly rotated 125

produce a high vacuum at the center of the rotor, thus causing an inrush of a mixture of oil and air, under the external atmospheric pressure, into the blower. The movement of air and oil takes place in the direction of the arrows (see Fig. 1) when the rotor is rotated at a high speed in the direction of the arrow A (see Fig. 1). It will be noted that as each of the primary blades 5 cuts into the mixture of oil and air, the portion in front of the blade will be thrown upwardly by reason of the curvature 36 in the blade. As this portion of the mixture moves upwardly it comes under the action 10 of the centrifugal force and is thrown upwardly into the secondary space 38' between the secondary blades and the primary blades. The oil particles in this mixture are broken up and more intimately mixed 15 through the action of the secondary and tertiary blades and by reason of the curvature of these blades the more intimately mixed oil and air is thrown through the tertiary spaces 39' and outwardly into the 20 space 46 between the rotor and the casing. All of the blades then serve to propel the mixture through the space toward the outlet 18.

A portion of the mixture of oil and air 25 under the rapid rotation of the primary blades is sucked or drawn up along the face 47 of the primary blades and into the secondary space 38' and under the action of centrifugal force is thrown outwardly 30 through this space as well as the tertiary spaces or pockets 39' into the space 46, at the same time the secondary and tertiary blades act to more finely divide the oil particles and more intimately mix the same 35 with the air.

In order to facilitate the passage of the mixture of oil and air through the space 46 and out of the casing through the outlet opening 18, and to prevent the same from 40 being carried around and around with the rotor, the passageway or space 46 is made curved and wedge-shaped. This construction is obtained by positioning the rotor with its axis off center, toward the outlet 18, 45 with respect to the center of the casing, thus bringing the blades very close to the inner side 47 of the wall 15 of the casing adjacent the upper edge 48 of the outlet opening 18, and remote from that portion of the inner side 47 of the wall 15 of the casing at the 50 point 49. It will thus be seen that between a point near the upper edge 48 of the outlet and the point 49 that the space within the casing between the outside surface of the 55 rotor and the inner side 47 of the wall 15 gradually increases in size. Although the blades are positioned very close to the inner side 47 of the casing, sufficient space is left so as to avoid any whistling or siren noises. 60 In order to prevent the oil from puddling 65

or settling into pools in the lower part of the blower, a series of auxiliary orifices are provided by positioning plates or baffles 50 adjacent the bottom of the casing in the outlet 18. These plates are secured to the 70 wall 14 of the casing and are adjacent to and angularly disposed with respect to the wall 15 of the casing, thus forming a plurality of orifices 50'. The action is such that the mixture of air and oil passing over 75 the upper surfaces of the baffles draws any oil which may have collected upon the wall 15 of the casing and under the baffles, into the mixture, such action being similar to that which occurs in atomizing a liquid by drawing air at high velocity over a jet in which the liquid is contained.

The rotor along its sides facing the walls 14 and 17 of the casing, fits the casing snugly so as to produce a stronger propelling action 85 of the blades or vanes upon the mixture of air and oil.

The rotor 21 as explained heretofore is secured to a shaft 23 which latter has one end 51 secured in any desired manner to the disk 90 22. By reason of this construction the rotor is supported by one bearing since the opposite side of the rotor is unsupported. The rotor may, however, be carefully balanced so that it runs true and noiselessly when rotated and especially at high speed. The long bearing 24 consisting of a cylindrical sleeve supported in the ends of the bearing box 26 prevents undue vibration of the rotor when actuated at high speeds. Lubrication of the bearing 24 may be provided for in the usual manner by an oil ring 52 and oil grooves 53. It is to be noted that the groove 53' of the lubrication conduits extends to a point in the end 25 of the bearing where it intersects or 95 meets a circular groove 54 cut in the shaft, another longitudinal groove 55, which has its end connected to and an aperture 56, passing through the bearing sleeve 24. By reason of this construction, oil is prevented 100 from passing the bearing box 26 within the casing 12 and mingling with the mixture of oil and air therein to disturb the consistency of the mixture. The bearing box 26 may be provided with a cover plate 26'. 105

The bearing box is provided with a stuffing box 58, through which the shaft 23 extends to be connected in any suitable manner to a driving shaft (not shown), connected to a source of power such as an electric motor 110 (not shown).

A lubrication channel 53'' may be provided in the bearing sleeve 24, this channel extending to a point within the stuffing box 58, a drain opening 60 being provided through 115 the end wall 60' of the casing to prevent an over accumulation of oil in the stuffing box. Thrust collars 61' and 60'' are provided and disposed between an internal annular flange 62' and the wall 60' of the bearing box to 120 125 130

In order to prevent the oil from puddling

take up end play of the shaft 23. Packing 63' may be inserted in the space 63" between the cover plate 64' and the annular flange 62' to prevent oil in the stuffing box 5 from exuding therefrom.

The foregoing blower is compact and noiseless in operation, and together with the operating motor and carburettor may be placed within a small space adjacent a furnace. Furthermore, the action of the blower is such that the mixture of oil and air delivered to the burner is supplied in a uniform manner and without changing the relative proportion of the oil and air, whereby the 15 "cracking" operation upon the mixture produced by the special burner may be effectively carried out to form a combustible gas of the illuminating and heating type, that is a permanent gas.

Although a preferred embodiment of the invention has been illustrated and described it is to be understood that those skilled in the art may make modifications therein, however, such modifications are contemplated 25 as come within the spirit and scope of the invention as defined in the appended claims.

What is claimed is:

1. In a fuel propelling and mixing device, a rotor for the same comprising a circular 30 disk and an annular plate, spaced apart, a plurality of vanes connecting said disk and plate and dividing the space therebetween into a plurality of compartments, certain of said vanes having a length equal to about 35 half the width of said plate between its in-

ner and outer edges and others of said vanes having the length substantially equal to the width of said plate and others of said vanes having a length greater than the width of said plate and extending to near the center 40 of said circular disk.

2. In a fuel propelling and mixing device, a rotor for the same comprising a disk having a plurality of radially disposed vanes extending at an angle to the face of said disk, said vanes having a reverse curvature, one curve lying near the center of said disk and the other near the outer edge thereof, said outer curve being of larger radius than the inner curve. 45

3. A fuel propelling and mixing device comprising a casing, a shaft in said casing, said casing having an increasing diameter in one direction of rotation about said shaft to an outlet opening, a rotor comprising a 50 plate mounted on said shaft at right angles to its axis, vanes projecting from a face of said plate and arranged in a radial manner about said shaft, said vanes being concave to a direction of rotation of said rotor plate adjacent their inner ends and curving reversely to a convex curvature at their outer ends, said casing having a central inlet about said shaft, the inner edges of said vanes sloping outwardly 55 towards said outlet opening. 60

In testimony whereof I affix my signature.

JOHN MURTON BROWN.
